UNITED STATES PATENT OFFICE

MICHAEL SOPSKO, OF CLEVELAND, OHIO

VANITY CASE

Application filed February 26, 1932. Serial No. 595,367.

This invention appertains to new and useful improvements in toilet articles and more particularly to a novel vanity case for ladies.

The principal object of this invention is to provide a novel vanity case wherein means is provided for easily and conveniently extracting a lip stick or eye brow pencil without opening the case.

Another important object of the invention is to provide a vanity device in the form of a container from which a lip stick or eye brow pencil can be projected by simple and convenient operation.

These and other important objects and advantages of the invention will become apparent to the reader of the following specification.

In the drawings:—

Figure 1 represents a perspective view 20 of the case in its entirety with the eye brow pencil extended.

Fig. 2 represents a perspective view of the container.

Fig. 3 represents a perspective view of the 25 article supporting partition.

Fig. 4 represents a perspective view of the lid.

Fig. 5 represents a top plan view of the vanity case with the lid removed.

Fig. 6 represents a longitudinal sectional view through the vanity case.

Fig. 7 represents a sectional view taken substantially on line 7—7 of Fig. 5.

Fig. 8 represents a cross sectional view taken substantially on line 8—8 of Fig. 6.

Referring to the drawings wherein like numerals designate like parts, it can be seen that numeral 5 represents the container and numeral 6 represents the lid, each of which is provided with a rectangular-shaped portion A and a curved portion B merging therewith. The rectangular end portion of the lid 6 is provided with an elongated hinge barrel 7, while the rectangular end portion of the container 5 is provided with a pair of widely spaced shortly hinged barrels 8—8.

The numeral 9 represents an article supporting partition plate which is provided with a laterally disposed flange 10 at its perimeter for snug disposition within the curved

portion B of the container 5. The plate 9 is also provided with a portion A and a portion B and in back of the portion A, the flange 10 is separated from the plate 9, disposed inwardly as at 11, and longitudinally as at 12, this construction being provided at each end of the flange 10 making a pair of such inwardly and longitudinally disposed portions, each of which is provided with a slot 13 extending longitudinally, the slots of the portions at 11 each end of the flange 10 merging as in the manner shown in Fig. 3.

The rectangular end portion of the plate 9 is provided with a pair of hinge barrels 14—14, which engage within the barrels 8—8, while the barrel 7 of the lid 6 engages within the barrels 14—14, so that when the hinge pin 15 is inserted through these barrels, these elements 5, 6 and 9 will be hingedly connected together.

At the rectangular end 8 of the plate 9 is the pair of plates 16—16 for snug disposition against the end wall of the container 5 at the rectangular end portion thereof and in these plates 16—16 are the openings 17—18 for registry with the openings 19—20 respectively of the end walls of the container 5 last mentioned.

With the partition plate 9 in the container 5, the offset portions of the flange 10 define pockets 21—22 in one of which can be placed the eyebrow pencil 23, while in the other a lipstick holder 24 may be placed, each of these holders being provided with oppositely disposed lug 25 slidably disposed through the slot 13 of the adjacent end portion of the flange 10. These lugs 25 loosely engage into the bifurcated ends 26 of complementary levers 27, there being a pair of levers which are pivotally connected together at their intermediate portions as at 28, and fixedly at this point to the back wall of the container 5 as at 29.

These levers 27—27 have offset end portions 30—30 which when mounted on the pivot 28 and in centralized position are substantially parallel. The end portions 30—30 are provided with lugs 31 and between these lugs is interposed the extensible coiled springs 32, 33.

for normally retaining the end portions 30—30 tensionally contracted.

As can be observed in Fig. 2, the last-mentioned end portion of the container 5 is provided with a slot 33 therein along which the pin 34 is slideable. A triangular-shaped member 35 is secured by straight portions to the pin 34 and depends between the lever end portions 30—30 as in the manner shown in Fig.

10 6. This pin 34 extends through the intermediate portion of a slide closure 36 which when in the position shown in Fig. 6, closes the openings 19—20 in the rectangular end of the container 5.

15 The partition plate 9 is provided with a pocket 37 for the rouge applicator 38 and rouge cake 39 and this plate 9 is also provided with the pocket 40 for the powder cake 41 and powder puff 42.

20 It can now be seen, that with the lid 6 spacing the user of this vanity case, the sliding of the closure 36 toward the right will expose the opening 20, and simultaneously the pressure of the actuator 35 against the lever end portion on the right will result in the projection of the eye brow pencil 23 through the opening 20. Obviously, by reversing the motion of the closure 36 so that the opening 19 is exposed, the corresponding exertion of force 25 against the lever extension or end portion 30 on the left in Fig. 6 will result in the lifting of the lip stick holder 24 so that the lip stick will be exposed through the opening 19.

25 While the foregoing specification sets forth the invention in specific terms, it is to be understood that various additions such as a mirror 43, fastening means 44 and other features can be added or removed, and that various other changes can be effected without affecting the spirit and scope of this invention as 30 claimed hereinafter.

35 Having thus described my invention, what I claim as new is:—

40 1. In combination, a container, said container having a pair of openings therein, a pair of slideable article holders in the container alined with the said openings, a single closure for the openings, and connections between the closure and the holders whereby the 45 holders will be moved toward the openings when the closure is disposed in opened position.

50 2. In combination, a container having a pair of openings therein, a pair of slideable article holders in the container alined with the said openings, a slideable closure disposed over the openings, a pair of rockable members on a single fulcrum, a member carried by the closure and being operative against 55 one end of each of the rockable members, the remaining ends of the rockable members being connected to the said holders.

55 3. A vanity case of the character described comprising a container, a pair of slideable cosmetic holders in the container, said con-

60 tainer being provided with openings toward which the holders are movable, and singular actuating means for the holders whereby the holders can be alternately moved toward their corresponding openings.

65 4. A vanity case of the character described comprising a container, said container being provided with a pair of openings, a pair of slideable cosmetic holders in the container mounted for slideable projection through the 70 openings, a slideable closure for the said openings, a triangular shaped formation on the closure, a pair of rockable members, spring means between the members bearing one end of each rockable member against the triangular formation, the remaining ends of the said 75 rockable members being engaged with the holders, whereby the holders are moved through the openings when the closure is moved.

80 In testimony whereof I affix my signature.
MICHAEL SOPSKO.
